UNITED STATES PATENT OFFICE

153,941

DESIGN FOR A BOTTLED BEVERAGE COOLER

Warner W. Hoople, Dallas, Tex., assignor to Dr.
Pepper Company, Dallas, Tex., a corporation of Colorado

Application June 28, 1948, Serial No. 147,248

Term of patent 7 years

(Cl. D67—4)

To all whom it may concern:

Be it known that I, Warner W. Hoople, citizen of the United States, residing at Dallas, in the county of Dallas and State of Texas, have invented a new, original, and ornamental Design for Bottled Beverage Cooler, of which the following is a specification, reference being had to the accompanying drawings, forming part thereof.

In the drawings:

The end and side of the cooler, not shown,

are substantially similar to the end and side shown.

I claim:

The ornamental design for a bottled beverage cooler, as shown and described.

WARNER W. HOOPLE.
